K. W. BARRAGER.
ADJUSTABLE SHADE ROLLER HANGER.
APPLICATION FILED JUNE 16, 1914.

1,144,283.

Patented June 22, 1915.

UNITED STATES PATENT OFFICE.

KENNETH W. BARRAGER, OF ATLANTIC HIGHLANDS, NEW JERSEY.

ADJUSTABLE SHADE-ROLLER HANGER.

1,144,283.

Specification of Letters Patent. Patented June 22, 1915.

Application filed June 16, 1914. Serial No. 845,404.

To all whom it may concern:

Be it known that I, KENNETH W. BARRAGER, a citizen of the United States, residing at Atlantic Highlands, in the county of 5 Monmouth and State of New Jersey, have invented certain new and useful Improvements in Adjustable Shade-Roller Hangers; and I do hereby declare the following to be 10 a full, clear, and exact description of the invention, such as will enable others skilled in the art to which it appertains to make and use the same.

This invention comprehends certain new and useful improvements in shade roller 15 hangers and has for its primary object to provide a device of this character which will be adjustable and of extremely simple construction and operation as well as cheap to manufacture and easy to secure in position.

Another object of the invention is to provide a device of this character which will be of such construction that it may be readily adjusted to windows of various 25 widths and the supports for the opposite ends of the shade roller adjusted upon the sectional body of the device, to properly support the shade roller.

This invention has for a further object to 30 provide a device of this character which will be constructed in such manner that the parts will be resiliently retained in adjusted position thereby assuring the shade thereof being properly held in suspended position and 35 also preventing disengagement of the sections of the body of the device from the window frame.

With these and other objects in view as will become more apparent as the description 40 proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a front elevation of the complete device in use, Fig. 2 is a longitudinal section through the device removed, with one end thereof broken away, Fig. 3 is a detail perspective view of the outer end of one of the sections of the body, Fig. 4 is a 55 detail perspective view of one of the shade

roller supports, and Fig. 5 is a similar view of the opposite shade roller support.

Referring more particularly to the drawings in which similar reference characters designate corresponding parts throughout the several views, 1 designates one section of the body of the device, while 2 designates the opposite section slidably mounted upon the same and adapted to be guided in its longitudinal movement by means of the 60 guide pins 3 carried thereby adjacent the inner end of said section 2 and engaged through the elongated longitudinal slot 4 formed in the inner end of the section 1, thereby making it impossible for one of the 65 sections of the body to move laterally independently of the other section. The sections 1 and 2 are also provided upon their outer ends with the inwardly directed claws 5 and 6 respectively for engagement in the opposite 70 sides of a window frame 7 or the like, to properly support the complete device in position, the sections 1 and 2 being drawn upon one another and resiliently retained in proper position by means of a helical spring 75 8 which has one end secured to the stationary pin 9 carried by the section 1, while its opposite end is secured to the upwardly curved inner end 10 of the section 2. It will be readily seen that this spring 8 will 80 serve to draw the claws 5 and 6 toward one another and retain said claws in engagement with the opposite sides of the window frame 7 after the sections 1 and 2 have been drawn outwardly upon one another and the claws 5 and 6 properly engaged in said window frame 7.

Mounted upon the outer face of the section 1 is a shade roller support 11 which has its outwardly directed free outer end 12 with 95 a suitable opening 13 provided therein for receiving one end of a shade roller upon which the shade 14' is mounted. The support 11 is slidably mounted upon the section 1 of the body and is guided in its longitudinal movement by means of the guide pins 14 projecting outwardly from the body section 1 and engaged through the elongated longitudinal slot 15 formed in the support 11, thereby preventing independent lateral movement of said support 11 upon the body section 1. The inner end 16 of the support 11 is curved upwardly and has one end of a helical spring 17 secured therein, while the opposite end of said spring 17 is se- 100 105 110

cured to the pin 9, previously mentioned, whereby said support 11 will be resiliently retained in its innermost position and prevented from moving outwardly after the shade roller has been secured in position. It will be seen that the pin 9 serves a double purpose as both the spring 8 and the spring 17 are secured thereto and extended in opposite directions.

10   Mounted upon the body section 2 at its outer end is positioned a shade roller support 18 which is adapted to be guided in its longitudinal movement upon said body section 2 by means of the guide pins 19 carried by said body section 2 and projecting through the elongated longitudinal slots 20 in said roller support 18. The shade roller support 18 is resiliently retained in its innermost position and prevented from moving outwardly after the shade roller has been placed in position and secured in said supports 11 and 18, by means of the helical spring 21 which has one end secured to the outwardly curved inner end 22 of said support 18, while its opposite end is secured to a pin 23 carried by said body section 2. It will be understood that the outer end of the support 18 is extended outwardly, as shown at 24, and provided with a suitable opening 25 to receive one end of the roller upon which the shade 14' is mounted.

From the foregoing it will be readily seen that I have provided a shade roller hanger which will be composed of the minimum number of parts and may be readily adjusted for window frames and shade rollers of various sizes, and should any of the parts become worn or broken, they may be readily replaced at a small cost.

40   While I have shown and described the pre-

ferred embodiment of my invention, it will be understood that minor changes in the details of construction, combination and arrangement of parts may be made without departing from the spirit and scope of the invention as claimed or sacrificing any of the advantages thereof.

What is claimed is:—

An adjustable shade roller hanger comprising a body section provided near its inner end with a longitudinally extending elongated slot, another body section having an overlapped engagement with the first named body section, guide pins carried by said other body section and passing through 50 said elongated slot to adjustably connect the sections, a claw formed on the outer end of each body section, an upturned lug formed on the inner end of said other body section, a contractile spring secured at one end to 55 said first named body section and at its other end to said lug, a pair of shade roller supports, each of said supports being provided with an elongated slot extending longitudinally thereof, guide pins carried by the sections and passing through the slots of the supports to adjustably mount a support upon each section, lugs formed on the inner ends of said supports, a contractile spring secured to the lug of one of the supports and 60 to one of the body sections, and another contractile spring secured to the lug of the other support and to said other body section.

In testimony whereof I affix my signature in presence of two witnesses.

KENNETH W. BARRAGER.
